COMBINED TELEPHONE HANDSET SUPPORT AND EQUIPMENT HOUSING OR SIMILAR ARTICLE**George M. Janda, Westchester, Ill., assignor to Automatic Electric Laboratories, Inc., Northlake, Ill., a corporation of Delaware****Filed Nov. 30, 1967, Ser. No. 9,596****Term of patent 14 years****U.S. Cl. D26—14
Int. Cl. D14—03**

FIG. 1

FIG. 2

FIG. 3

FIG. 4

FIG. 5

FIG. 1 is a front, right side and top perspective view of a combined telephone handset support and equipment housing or similar article, showing my new design;

FIG. 2 is a top plan view;

FIG. 3 is a front elevational view;

FIG. 4 is a left side elevational view thereof; and

FIG. 5 is a rear elevational view.

The dominant features of my design reside in the portions shown in full lines.

I claim:

The ornamental design for a combined telephone handset support and equipment housing or similar article, as shown and described.
